5 U.S. CL. 214—135 8 Claims
Int. CL. A63h 17/12; B62m 1/14; E02f 3/02

ABSTRACT OF THE DISCLOSURE

A toy shovel having a mobile platform; an operating platform pivoted to said mobile platform; a seat on said operating platform; a boom pivoted to said operating platform; a scoop arm pivotally and slidably mounted on the boom, and manually operable means on the operating platform, and within arm length of the seat, for performing all functions of the shovel.

This invention relates to toy power shovels of the sit-on type in which all functions of the shovel are manually operable from the operator's seat.

From time immemorial, children have enjoyed emulating adult activities, and toys to facilitate such emulation are quite beyond number. Of late, so far as toys are concerned, there is a trend toward child participation rather than mere observation. Emulation by observation and partial participation readily is accompanied by means of miniature toys. The current trend calls for the child actually "to occupy the driver's seat" and thereby participate fully or at least as fully as cost and engineering design of the toy will permit, in the complete emulation of the activity for which the toy is designed. This is the basic principle of the "sit-on" type of toy.

It is accordingly an object of this invention to provide a toy power shovel having a seat for the operator located where the operator would sit on the full scale model and to have within reach of this seat manually operable controls whereby the child while seated can operate the toy for all of the functions of which it is capable.

It is a further object of this invention to provide a toy power shovel as aforesaid in which the manual controls operate directly to perform the several functions of the machine.

The above and other objects will be made clear from the following detailed description taken in connection with the annexed drawings, in which:

FIGURE 1 is a side elevation of the improved toy;
FIGURE 2 is a top plan view of the top shown in FIGURE 1;

FIGURE 3 is a front elevation partially in section, taken on the line 3—3 of FIGURE 1;

FIGURE 4 is a plan view partially in section taken on the line 4—4 of FIGURE 1;

FIGURE 5 is a vertical cross section taken on the line 5—5 of FIGURE 4;

FIGURE 6 is a detail of a crank and its holding means, several of such cranks and holding means being used in the machine;

FIGURE 7 is a partial section of the line 7—7 of FIGURE 6;

FIGURE 8 is a perspective view of an optional boom construction; and

FIGURE 9 is a perspective view of an optional attachment whereby the toy is converted from a power shovel to a drag scoop type of construction.

Referring now to FIGURE 1, the toy has a base 10 rendered mobile by Caterpillar tracks 12 and on the mobile base or platform 10 there is an operating platform 14 which is pivoted to the mobile platform 10. A seat

2

16 is mounted on the platform 14 and faces a boom generally indicated as 18, the boom being secured to the operating platform 14 by a horizontal pivot 20. A column 22 is also mounted on the operating platform 14 and, as will appear hereinafter, the column 22 forms a support for a number of manually operable means for performing the several functions shown.

Referring now to FIGURES 1 and 2, the boom 18 is made up of parallel members 24 which at one end engage a pivot pin 20 and at their opposite ends engage a pivot pin 26 and have a sheave 28 mounted between them and rotatable on the pin 26. Each of the members 24 has attached at the end adjacent the sheave 28 an eyelet 30 for a purpose presently to be described.

Somewhat more than midway their length, toward the pivot pin 26, the members 24 are pierced by a pivot pin 32, on which is mounted between the members 24 a scoop arm 34. This arm has a longitudinal slot 36 through which the pin 32 passes so that scoop arm 34 may slide longitudinally on the pin 32 and also rotate thereabout.

Referring now to FIGURES 1, 4, and 5, the operating platform 14 rests on rollers 38 which are supported in brackets 40 mounted on the mobile platform 10. Centrally between the rollers 38 there is mounted on the mobile platform 10 an internally toothed ring gear 42 having a central boss 44 penetrated by a sleeve bearing 46. A stub shaft 48 penetrates the sleeve bearing 46 and has at its lower end a bevel gear 50. Its upper end penetrates the operating platform 14 as does the upper end of the sleeve bearing 46. The bearing 46 also acts as a pivot bearing for the operating platform 14 and has threaded connection with a guard sleeve 52 which shields an actually detachable joint 54 formed between the stub shaft 48 and an operating shaft 56. The operating shaft 56 passes through a supporting member 58 which is secured to the column 22. The shaft 56 terminates at its upper end in a crank 60.

Below the bevel gear 50, best seen in FIGURES 4 and 5, a shaft 62 penetrates the side walls of the mobile platform 10 and has keyed thereto a bevel gear 64 meshing with the bevel gear 50 and at the opposite side of stub shaft 48. There is also keyed to the shaft 62 a sprocket 66.

Also journalled in the side walls of the platform 10 are axles 68 and 70, each of which has at each end thereof a wheel 12. The wheels 12 at each side of the platform 10 act as sprockets for carrying Caterpillar belts 72. The wheels 12 on shaft 68 are keyed thereto and the shaft also carries a sprocket 74 connected to the sprocket 66 by a chain 76. Accordingly, upon manual rotation of the crank 60, the caterpillar treads may be moved in a forward or backward direction to move the platform 10 and the rest of the parts mounted thereon as the operator may desire.

Also penetrating the platform 14 is a shaft 78 having at its upper end a crank 80 and at its lower end a pinion 82 meshing with the ring gear 42. When the operator on seat 16 turns the crank 80, the pinion 82 will travel around the interior of the ring gear 42, thereby swinging the platform 14 around the sleeve 46 as a pivot.

Referring now to FIGURES 1, 2 and 3, the control and function of the boom 18, the scoop arm 34 and their associated parts will now be described. The boom 18 is raised and lowered by means of a windlass shaft 82 having a crank 84 formed at one end with the shaft 82 acting as a windlass for a pair of lines 86 which are attached by S-hooks 88 to the eyes 30 of the members 24 making up the boom 18. The shaft 82 is mounted in a pair of ears 90 projecting forwardly from the top of the column 22. Naturally, it will be desirable at times to lock the boom 18 in a desired position. This is true of other cranks presently to be described. The locking means

for all of these cranks are identical, are illustrated in detail in FIGURES 6 and 7 and will be described with reference to those figures in connection with the shaft 82 and crank 84 but the description is equally applicable to the other cranks.

Referring to FIGURES 6 and 7, the shaft 82 is shown adjacent the crank 80 where it passes through one of the ears 90. An aperture 92 is formed in the ear 90 slightly above the shaft 82. A piece of rod stock 94 is bent to provide a lower portion 96 which is welded to the shaft 92 adjacent the crank 80 and an upper portion 98 which lies slightly above the shaft 82 and sized to penetrate the aperture 92. When it is desired to operate the crank 80, the crank and its shaft 82 are pulled axially to the right of FIGURE 6, withdrawing the rod 98 from the aperture 92. After operation of the crank 80 to the desired position of the boom, the crank 80 and the shaft 82 are slid axially to the left of FIGURE 6 so that rod 98 enters the aperture 92, locking the crank in that position.

As previously noted, the scoop arm 34 is both longitudinally slidable and rotatable about the pin 32 mounted in the boom 18. Referring now to FIGURES 1 and 2, a bucket or scoop 100 is secured at 102 to the forward end of the scoop arm 34. A projecting arm 104 carrying a sheave 106 is secured to the arm 34 at its opposite end. Mounted in the column 22 (FIGURE 3) is a shaft 108 having at one end a crank 110 equipped with a holding member 94 similar to that described with reference to FIGURES 6 and 7. A windlass 112 is secured to the shaft 108 and carries a line 114. As shown in FIGURE 1, the line 114 runs from the windlass 112 over a sheave 116 secured to the boom 18, thence over the previously mentioned sheave 106 at the rearward end of scoop arm 34, thence over the sheave 28 at the outer end of the boom 18, thence around a sheave 118 which is rotatably mounted on an axle 120 which is supported by a pair of bracket arms 122 secured to the scoop or bucket 100 from the sheave 118. The line 114 is secured at 124 to the forward end of the boom 18.

As line 114 is wound up on the windlass 112, it performs two distinct functions. Through the sheave 118 the line 114 exerts a lifting effect on the bucket 100, thereby tending to rotate the arm 34 about the pivot pin 32. At the same time, the line 114 forms a force triangle between the sheaves 28, 106, and 116, the resultant of which tends to slide the arm 34 via the slot 36 across the pin 32. There is thus produced a close approximation of the classic "steam shovel" effect.

The operations of dumping the scoop 100 and retracting the scoop bar 34 preparatory to a new scoop action will now be described. Referring now to FIGURE 3, the shaft 130 is mounted in the column 22 and has at one end the crank 132 and adjacent the crank the usual holding means 94. A pair of windlasses 134 and 136 respectively carry lines 138 and 140. As shown in FIGURE 1, the line 140 runs over a sheave 142 mounted on the boom 18 and its free end is attached to the scoop arm 34 by means of a bracket 144. The line 138 passes over a sheave 146 attached to the boom 18 and has its free end attached to a link 148, pivoted at 150 to the scoop arm 34. A spring 152 biases the link 148 toward the bucket 100, while a conventional, slack flexible tension member connects the link 148 to the usual dump bottom 156 of the bucket 100 which has the usual pivot 158 adjacent the rear end of the bucket 100.

As shown in FIGURES 1 and 3, a foot treadle 160 is provided on the platform 14 adjacent the column 22. The treadle 160 is biased by a spring 162 to its upward position and at its free end is secured to a bent rod 164 which terminates in an upper loop 166. The loop 166 surrounds line 138. Now assume the parts to be in the position of FIGURE 1 with the shaft 130 in locked position as shown in FIGURE 3. The depression of the pedal 160 will draw down on the member 164, the loop 166 of which will

jerk on the line 138, free the latch of the gate 156 and dump the bucket 100. Release of the treadle 160 permits the spring 164 to return it to a normal upward position, permitting the spring 152 to swing the link 148 toward the bucket 100 and thus permit the bottom gate 156 to latch itself back into the position of FIGURE 1, as is conventional practice in full scale operations.

As a result of the operations described in the preceding paragraph, the machine is ready for a new scooping cycle. To accomplish this, both the shafts 108 and the shaft 130 are freed of the holding means 94. The weight of the bucket 100 unbalances the scoop bar 34 which being unopposed either by the sheave 118 or the sheave 106 tends both to pivot and slide about the pin 32. In order to insure optimum retraction of the bucket to a position where the scoop bar 34 is substantially vertical, the line 140 is wound up on its winch 136 by means of the crank 132 until the desired position of the bucket 100 is reached and with crank 132 and shaft 133, crank 110 is turned to wind up the line 114 and repeat the previous cycle. During the cycle, of course, as the bucket 100 extends outwardly from the platform 14, the lines 138 and 140 are free to accompany its movement.

Referring back to FIGURE 5, it must be emphasized that shaft 56 by axial movement may be withdrawn from engagement with the shaft 48. The reason for this is that in any given position of the mobile base 10 several scoop operations will be conducted, usually with swinging movement to the operating platform 14 between cycles. If then it is desired to advance the machine as a whole, the shafts 56 and 48 are reengaged and crank 60 is turned to advance or retract the machine by means of the tracks 72.

FIGURES 8 and 9 are included chiefly to illustrate the versatility of this toy and the parts of FIGURES 8 and 9 serve to convert the machine from scoop shovel operations to drag line operations. In FIGURE 8, the boom is made up of longitudinal members 200 and 202. The only reason a separate boom is required is that drag line operations require a much longer boom than the boom 18 which is only suitable for scoop shovel operations. Each of the members 200 and 202 has an eye 30 precisely similar to the eyes formed in the members 24. At the rear end the members 200 and 202 have apertures 204 which fit on to the pivot pin 20. At the front end these members have the same pivot pin 26 and sheave 28 as is used in the boom 18. The eyes 30 connect to the lines 86 precisely as is the case in FIGURE 1 and the main line 114 runs directly over the sheave 30 and is secured to an S-hook 206, attached to a chain or cable 208 which is secured to a drag scoop 210. Above the scoop 210 the arms of the chain 208 are spaced by a rod 212. A pair of chains 214 run from the front end of the bucket 210 to a drawbar 216 to which the chains 214 are attached by S-hooks. Line 218 runs from the drawbar 216 over a pulley 220 which is also secured to the S-hook 206. The free end of the line 218 is secured to an S-hook 222 on a bracket 224 attached to the upper side walls of the scoop 210 adjacent its front or open end. The drawbar 216 has a forward S-hook 226 for attachment to either of the lines 138 or 140 which both are operable by means of the crank 132 shown in FIGURE 3.

While certain specific details of construction have been disclosed herein, various modifications in the structures may be made without departing from the spirit of this invention which is to be limited only as set forth in the subjoined claims.

What is claimed is:

1. A toy power shovel of the mobile, sit-on type comprising: a mobile base in contact with the ground; an operating platform mounted for rotation on said base; a boom pivoted to said platform; an operator's seat mounted on said platform and facing said boom; a vertical column on said platform between said seat and said boom; a plurality of manually rotatable cranks mounted

in said column; a connection between one of said cranks and the free end of said boom for raising and lowering the same; a fixed pivot mounted intermediate the ends of said boom; a scoop arm rotatably and slidably mounted on said pivot, a scoop bucket mounted on said scoop arm; a connection running between a second of said cranks to the end of said scoop arm opposite said bucket, thence to the free end of said boom, thence to said bucket and back to said boom; a connection between a third of said cranks and the bucket end of said scoop arm for drawing said bucket toward said platform, and means for locking, at will, any of said cranks against rotation.

2. The toy of claim 1, in which said crank locking means comprises a projection on each crank engageable and disengageable with said column by axial movement of such crank.

3. The toy of claim 1, in which said bucket has a dumpable bottom; a connection between said third of said cranks and said bottom for dumping the same, and a foot treadle adjacent said column for operating said connection.

4. The toy of claim 3, in which said crank locking means comprises a projection on each crank engageable and disengageable with said column by axial movement of such crank.

5. The toy of claim 1, including a vertical axis manu-

ally rotatable crank between said seat and said column for moving said mobile base.

6. The toy of claim 5, in which said vertical axis crank is removable at will.

5 7. The toy of claim 5, including a second vertical axis manually operable crank for rotating said platform on said base.

10 8. The toy of claim 6, including a second vertical axis manually operable crank for rotating said platform on said base.
